UNITED STATES PATENT OFFICE.

CHARLES A. HORNBURG, OF WACO, TEXAS.

DOORCHECK.

Application filed April 24, 1923. Serial No. 634,338.

To all whom it may concern:

Be it known that I, CHARLES A. HORNBURG, a citizen of the United States, residing at Waco, in the county of McLennan and 5 State of Texas, have invented a new and useful Doorcheck, of which the following is a specification.

This invention relates to a door check, one of its objects being to provide a check 10 which will allow a door to swing rapidly for a portion of its distance of travel after which it will be automatically retarded until the door nearly reaches its closed position at which time the door is released automatically 15 and is allowed to close tightly against the jamb.

Another object is to provide novel friction 20 means for retarding the movement of the door, there being means for automatically coupling the door to and uncoupling it from the friction means during the movement of the door toward its closed position.

A further object is to provide a door check 25 which is simple and compact, can be applied readily, and has means whereby it can be easily adjusted to vary its resistance to the actuation of the door.

With the foregoing and other objects in view which will appear as the description 30 proceeds, the invention consists of certain novel details of construction and combination of parts which will be hereinafter more fully described and pointed out in the claims, it being understood that various 35 changes may be made in the construction and arrangement of the parts without departing from the spirit of the invention as claimed.

In the accompanying drawing the preferred forms of the invention have been 40 shown.

In said drawings:

Figure 1 is an elevation of the check, a portion of the door and jamb being shown in elevation and section respectively.

Figure 2 is an elevation of the parts, the door being shown open.

Figure 3 is a plan view showing the door closed as in Figure 1.

Figure 4 is a plan view showing the door open as in Figure 2.

Figure 5 is a section on line 5—5 Figure 2.

Figure 6 is a plan view showing a modified construction.

Referring to the figures by characters of 55 reference A designates a portion of a door

jamb and B designates a portion of a door connected to the jamb by one or more hinges C.

The check includes superposed attaching plates 1 and 2 adapted to be fastened to the jamb A by screws 3 or the like extending through slots 4 whereby the plates can be adjusted toward or from each other. Each plate has a wing 5 extending at right angles therefrom, the two wings being of the same 60 contour and supporting a central clamping bolt 6 engaged by nuts 7 one of which bears downwardly on the upper wing 5 while the other bears upwardly against the lower wing 5. The greater portion of the peripheries of the wings are concentric with the bolt 6 but at intermediate points these peripheries are cut away as shown at 8 to provide recesses.

Mounted for rotation on the bolt 6 and between the wings 5 is a ratchet disk 9 the teeth of which are adapted to be exposed successively within the recess 8. Those teeth not exposed in the recess are positioned inwardly from the peripheries of the wings 70 as will be apparent by referring to Figures 3 and 4.

An arm 10 having a forked end 11 straddles the wings 5 and frictionally engages the exposed surfaces of the respective wings. The arms of the forked portion 11 are offset 85 as shown at 12 so as to bridge the nuts 7 and pivotally engage bolt 6. That end of the arm remote from the fork is connected by toggle links 13 to a bracket 14 attached to the door B. A light spring 15 is connected to the bracket 14 and bears against one of the links of the toggle so as to hold 90 said link normally pressed against the door.

A coiled spring 16 is connected at one end to the door and at its other end to a projection 17 on plate 1 and this spring is designed to pull the door to closed position when a hinge spring or other closing means is not used. This spring is adapted to engage a sleeve or roller 18 carried by one end portion of the bolt 6.

It is to be understood that the wings 5 engage the disk 9 with sufficient pressure to frictionally retard the rotation thereof. This disk is adapted to be actuated by a spring 105 pressed dog 19 mounted within the forked portion of the arm 10 and normally pressing against the peripheries of the wings 5. When the door is fully open and the parts are posi- 110

tioned as shown in Figure 4 the dog 19 bears against the peripheries of the wings and is held thereby out of contact with the frictionally held disk 9. At this time the spring 16 is under tension or, if spring 16 is not used, the spring of the hinge is under tension. Thus when the open door is released the spring will swing it toward closed position. During the greater portion of this movement the dog will slide freely along the peripheries of the wings but as the door continues to move, dog 19 will move into the recesses 8 and engage one of the exposed teeth of the disk. The dog will thus thrust 15 against the disk and rotate it and as the disk is held frictionally between the wings the movement of the door will be retarded. This retarded movement will continue until the door is almost closed at which time the dog 20 will be deflected by the walls of the recesses 8 so as to pass out of engagement with the disk. As the door is thus relieved from the retarding action of the disk its actuating spring will move the door the short remaining 25 distance so that said door will fit snugly against the jamb without slamming.

Spring 16 is not always used but it is a desirable portion of the structure because of its action while closing the door. When the 30 door is completely open the spring exerts a direct pull from one end to the other and this pull continues until the spring comes against the sleeve or roller 18. At this time the spring bends and acts as a cushion to retard 35 the closing of the door by reducing the power exerted, thus rendering the friction wings and disk more efficient.

Under some conditions it is desirable to have the arm of the check detached from 40 the door. Such a structure has been illustrated in Figure 6. When this structure is used a roller 20 can be carried by the arm for engagement with the door and a spring 21 can be connected to the arm and to the 45 plate 1 for the purpose of holding the roller constantly pressed against the door.

It is to be understood that the spring 16 need not be used if the door is provided with spring hinges.

50 What is claimed is:

1. A door check including a rotatable member, door operated means for engaging and actuating the member, friction means for retarding the rotation of said member and for holding the door operated means out of engagement with said member during the first and last portions of the movement of the door in one direction.

2. A door check including a rotatable 60 member, adjustably connected friction means engaging said member to retard the rotation thereof, door operated means slidably engaging the friction means, said friction means constituting guides for moving the door operated means successively into and

out of engagement with the rotatable member during the closing of the door.

3. A door check including a rotatable ratchet disk, friction means for retarding the rotation of the disk, an arm pivotally mounted relative to the disk and friction means, means for holding the arm in operative relation with a door, means carried by the arm for slidably engaging the friction means during the closing of the door, said friction means constituting a guide for directing the slideable means into engagement with the disk during an intermediate portion of the movement of a door toward one position.

4. A door check including a rotatable ratchet disk, friction means for retarding the rotation of the disk, an arm pivotally mounted relative to the disk and friction means, means for holding the arm in operative relation with a door, a dog carried by the arm for slidably engaging the friction means, said friction means constituting a guide for directing the dog into engagement with the disk to actuate the disk during an intermediate portion of the movement of the arm in one direction.

5. A door check including spaced adjustably connected friction members, a ratchet disk rotatably mounted therebetween and frictionally engaged thereby, an arm pivotally mounted relative to said members, means for holding the arm in operative relation with a door, a dog carried by the arm and slidably engaging the friction members, said members constituting guides for holding the dog out of engagement with the disk during the first and last portions of the movement of the arm in one direction and for directing the dog into engagement with the disk to actuate it during an intermediate portion of said movement of the arm.

6. A door check including adjustably mounted attaching plates, friction wings extending therefrom having coinciding recesses in their periphery, a ratchet disk rotatable between the wings and having a portion of its periphery exposed in the recesses, an arm pivotally mounted relative to the wings, means for holding the arm in operative relation with a door, and means carried by the door movable along the peripheries of the wings into and out of engagement with the exposed portion of the disk to actuate the disk during an intermediate portion of the movement of the arm in one direction.

7. A door check including a friction member having a recessed periphery, a ratchet disk engaged thereby and having a portion of its periphery exposed in the recess, an arm pivotally mounted relative to the friction member, means for holding the arm in operative relation with a door, a dog carried by the arm and movable along the pe-

riphery of the friction member into and out of engagement with the disk to rotate the disk, an actuating spring connected to the friction member for attachment to a door, and means for buckling the spring during its actuation of the door.

In testimony that I claim the foregoing

as my own, I have hereto affixed my signature in the presence of two witnesses.

CHARLES A. HORNBURG.
